GRAB RAIL FOR A SWIMMING POOL

Myron P. Anthony, Newport Beach, Calif., assignor to Anthony Pools, Inc., South Gate, Calif., a corporation of Delaware

Filed May 20, 1963, Ser. No. 74,971

Term of patent 14 years

FIGURES 2, 3 and 4 are front elevational, side elevational, and top views, respectively, thereof.

The broken line showing in the figures of the companion grab rail and the section of a deck and coping of a swimming pool are for purposes of illustration only.

I claim:

The ornamental design for a grab rail for a swimming pool, as shown and described.
